Atty's.

UNITED STATES PATENT OFFICE.

HENRY PEETERS, OF WARCOING, BELGIUM.

BACK-SPACING MECHANISM FOR TYPEWRITERS.

Application filed February 20, 1924, Serial No. 694,079, and in Belgium December 21, 1923.

This invention relates to an improvement in the mechanism for the return of the paper carriage for typewriters in which the said movement is controlled by a lever operated by hand, and the invention relates more particularly to a mechanism which allows the carriage to be moved in the direction opposite to that which corresponds to the automatic advance for typing, to a given distance which is generally that of a character to be printed, or of a space.

In known devices of this type the approach of the rack toward the finger is produced by displacing it in a direction which is inclined relative to the axis of the finger or else it is produced by the intermediary of a complicated mechanism. The interengagement of the finger by the rack is, therefore, not direct and as a result of this, after some little usage, the finger no longer engages behind the desired tooth of the rack which is actuated by pushing and thus renders the mechanism uncertain. Furthermore, at very high speeds, due to the haste of the operator, or due to the effect of the back spacing movement, which the carriage undergoes in contacting against a stop, it may occur that the rack will contact with the finger in an unforeseen position.

In the present invention the displacement of the rack toward the finger is produced by a hand lever in a direction perpendicular to its axis, while the movement in the back space direction of the carriage is produced by a mechanism which is automatic and is independent of the said lever.

For this purpose, according to the invention, this hand lever can move angularly along a graduated scale while drawing along the spindle which causes the engagement of the rack with the finger, and which moves them backwards a distance corresponding to the angular displacement of the hand lever.

This return movement is produced as soon as a bell-crank lever, pivoted to the support of the rack, and engaged by the movable spindle, pushes against a fixed abutment.

A construction according to the invention is illustrated by way of example in the accompanying drawings in which:

Figure 1 is a perspective view showing the various elements of the invention;

Figure 2 shows the said elements in elevation;

Figure 3 is a rear view of the device shown

in Figure 2, showing the position of the various elements during their operation.

Fig. 4 is a perspective view showing the various elements of a constructional form of the invention permitting a variable back spacing of the carriage.

In the drawings is represented one form of the invention, it being clearly understood that the invention is applicable to all typewriters in which the backward movement of the carriage is effected by acting on a finger rigidly connected to the carriage.

According to this form, movement of the carriage in both directions is controlled by an operating member 106, 117, which is connected to the carriage so as to be moved with the latter in a direction parallel to the carriage. Rod 106 with handle 120 controls the escapement mechanism, and rod 117, on movement from left to right causes the return of the carriage, while its movement by means of handle 121 operates the interlining mechanism. These rods 117 and 106 are interconnected by a collar member 118 so as to be moved together bodily, while being independently rockable.

On a second member (not shown) similar to 118, is mounted a pointer 136 travelling in a groove 137 in front of a graduated rule or scale 138 measuring the travel of the carriage.

The pointer 136 projects downwards in the form of a finger 150 which during the movement of the carriage moves near a rack 151, the teeth of which corresponds to the lengths of the spaces and which is supported by a rod 152 along which it slides. This rod 152 is keyed by means of the arm 154 to a pivoted spindle 153 mounted on the main frame of the machine the rotation of the said spindle in the direction indicated by the arrow, being controlled by the handle 155.

When it is desired to move the carriage back to a length corresponding to that of a character, the spindle 153 is turned in the direction indicated owing to which the rack 151 is brought into contact with the finger 150 supported by the rods 106, 117 rigidly connected to the carriage. The finger 150 engages behind the tooth of the rack 151, which is in the same vertical plane. At that moment, the bell-crank lever 156 pivoting about the spindle 157, strikes the stop 158 and pushes in front of it the rack 151 along the rod 152 which drives the control piece

constituted by the rods 106, 117 to a distance corresponding to a space.

The device thereupon automatically resumes the original position under the action 5 of the two springs 159—160.

Obviously, the amplitude of the movement depends more particularly on the shape of the lever 155, and the said shape is such that by turning the spindle 153 to the end of the 10 travel, the carriage is pushed back to the extent of a length of a character. Where characters of different lengths are utilized, as is the case in some oriental languages, the pivoting of the spindle 153 may be effected 15 in such a manner that, by moving the handle in front of a series of marks, the carriage is moved back to a length corresponding to one, two or more spaces. In order that this take place it is evident that the finger 150 cannot 20 pass to the bottom of the notches separating the teeth of the rack 151. A rack having notches of sufficient depth is shown in Figure 4. The drawing shows one form of this means, wherein is a graduated scale 161 on 25 which are graduations according to which the lever 155 should be moved, for back-spacing the carriage, one, two, or more spaces. This form is purely illustrative, and presents the disadvantage that there are 30 no limiting means for predetermined movements of lever 155. Of course this simple form can be replaced by any of the well known means for limiting the movement of lever 155. Furthermore, it is clear that multiple combinations may be made, without departing from the invention, as regards the 35 shape and the arrangement of the parts.

What I claim as my invention and desire to secure by Letters Patent is:

40 1. A back spacing mechanism for typewriters, comprising a finger rigidly connected to the carriage of the typewriter, a rack normally out of engagement with the finger, an elongated rod slidably carrying 45 the rack, a hand lever operable to move this rod and the rack normally towards the finger until engagement between the finger and the rack is produced, and means carried by the rod for sliding the rack along its rod after 50 said engagement, the displacement of the hand lever being continued.

55 2. A back spacing mechanism for typewriters, comprising a finger rigidly connected to the carriage of the typewriter, a rack normally out of engagement with the finger, an elongated rod slidably carrying the rack, a hand lever operable to move this rod and the rack normally towards the finger until engagement between the finger and the rack is produced, a bell-crank lever mounted 60 on the rod and arranged to bear against the rack, a fixed stop adjacent the bell-crank lever, the bell-crank lever being brought to bear against the stop simultaneously with 65 the interengagement of the finger and rack

to thereby cause a movement of the rack and finger in the back spacing direction of movement of the carriage, the displacement of the hand lever being continued.

3. A back spacing mechanism for typewriters, comprising, a finger rigidly connected to the carriage of the typewriter, an elongated rod, a rack carried by this rod and slidably lengthwise of the same, a spindle parallel with the rod, an arm interconnecting the spindle and rod, a fixed stop, a hand lever for rocking the spindle, a pivoted bell-crank lever bearing at times against one end of the rack and the fixed stop, rocking of the spindle by the hand lever moving the 70 rack to engage the finger normally therewith and simultaneously press the bell-crank lever against the stop to thereby slide the rack along the rod, and resilient means for returning the rack and hand lever to their 75 initial positions.

4. A back spacing mechanism for typewriters, comprising, a finger rigidly connected to the carriage of the typewriter, an elongated rod, a rack carried by this rod and slidably lengthwise of the same, a spindle parallel with the rod, an arm interconnecting the spindle and rod, a fixed stop, a hand lever for rocking the spindle, a pivoted bell-crank 80 lever bearing at times against one end of the rack and the fixed stop, rocking of the spindle by the hand lever moving the rack to engage the finger normally therewith and simultaneously press the bell-crank lever against the stop to thereby slide the rack along the rod, and resilient means for returning the rack and hand lever to their 85 initial positions.

5. A back spacing mechanism for typewriters, comprising, a finger rigidly connected to the carriage of the typewriter, an elongated rod, a rack carried by this rod, and slidably lengthwise of the same, a rockable 90 spindle parallel with the support, an arm interconnecting the spindle and support, a fixed stop, a pivoted bell-crank lever bearing 95 at times against one end of the rack and the fixed stop when rocking the spindle, a hand lever, a graduated scale member for the hand lever, the hand lever being mounted on the spindle which is displaceable angularly for moving the rack to engage the finger normally therewith, and simultaneously to press the bell-crank lever against the stop for sliding the rack along the rod a distance corresponding to the angular displacement of the hand lever along the graduated scale 100 member.

6. A back spacing mechanism for typewriters wherein the carriage is back spaced by a hand operated rod rigidly connected to the carriage, comprising a hand operated 105 110 115 120 125 130

rod, a finger positively connectable to the hand operated rod, a rod, a rack on this rod and slideable lengthwise thereof, a rockable spindle parallel with this rod, an arm inter-
5 connecting the spindle and rod, a fixed stop, a pivoted bell-crank lever bearing at times against one end of the rack and the fixed stop when rocking the spindle, a hand lever, a graduated scale member for the hand lever,
10 the hand lever being arranged to rock the

spindle and move the rack to engage the finger normally therewith and simultaneously to press the bell-crank lever against the stop for sliding the rack along the rod a distance corresponding to the angular displacement of ¹⁵ the hand lever along the graduated scale member.

In testimony whereof I affix my signature.

HENRY PEETERS.
